UNITED STATES PATENT OFFICE.

RUSSELL PARKER, OF NEW YORK, N. Y., ASSIGNOR TO THE PARKER,
STEARNS & SUTTON, OF SAME PLACE.

VAGINAL TUBE FOR SYRINGES.

SPECIFICATION forming part of Letters Patent No. 613,391, dated November 1, 1898.

Application filed January 4, 1898. Serial No. 665,579. (No model.)

To all whom it may concern:

Be it known that I, RUSSELL PARKER, a citizen of the United States, and a resident of New York, (Brooklyn,) in the county of Kings and State of New York, have invented a new and useful Improvement in Vaginal Tubes for Syringes, of which the following is a specification.

This improvement relates to the tubular attachments for syringes variously known as "vaginal tubes" and "vaginal irrigators." Such tubes or tubular attachments have heretofore been constructed entirely of a comparatively rigid substance, such as hard vulcanized india-rubber, in order to give them such stiffness lengthwise as it is desirable they should have.

The object of this invention is to obtain a tube or tubular attachment of this kind which possesses the desirable degree of stiffness lengthwise without making its walls so rigid as to render them unpleasantly or prejudicially hard or unyielding in other directions.

I will now proceed first to describe the invention with reference to the accompanying drawings of a vaginal tube or irrigator embodying the invention, and afterward point out its novelty in claims.

Figure 1 in the drawings is a longitudinal view representing the tube with a portion of its exterior broken away to display the improvement; Fig. 2, a section in the line 2 2 of Fig. 1, and Fig. 3 a transverse sectional view illustrating a modification.

Similar letters of reference designate corresponding parts in all the figures.

A is the tube, which may be and is represented as constructed of soft vulcanized india-rubber of a shape and size corresponding with the hard-rubber tubes of the kind in common use. This tube has located lengthwise within its walls or body several (not less than three) thin flat strips $a a' a'' a'''$ of spring-steel, the said springs being at equal distances apart and having their flat sides toward the internal and external circumferences of the tube, so that any tendency to bend the tube in the direction of the least dimension of any strip or spring is resisted by others of the strips which have their greater dimensions and

greater capability of resisting flexure presented in or approximately in the same direction—for instance, in the example shown in Fig. 2, in which there are three strips or springs. Any tendency to bend the tube in 55 either direction toward the flat sides of the strip or spring a as presented will be resisted by greater dimensions of the two strips or springs $a' a''$ being presented in an approximately corresponding direction, and in like 60 manner any tendency of the tube to bend in the direction of the least resistance of any one strip or spring will be met by greater resistance of the other strips or springs, each strip or spring thus constituting a brace to 65 the others. In the example shown in Fig. 3, in which there are four strips or springs, any tendency of the tube to bend in the direction of the strips or springs $a a''$ is met by the greater resistance of $a' a'''$, and vice versa, the 70 greater dimensions of either two opposite springs being presented in the same direction as the lesser dimensions of the other two.

The introduction or incorporation of the strips or springs within the soft-rubber walls 75 of the tube may be effected in any manner known in the rubber manufacture for introducing metal into rubber fabrics. They may be so incorporated loosely or without adhesion to the body of the tube either at their ends 80 or at any point in their length, thereby permitting such slight elongation of the tube as may be desirable or unobjectionable in use. They may extend to the extreme ends of the tube or terminate near the ends, as shown by 85 the dotted representation of them in Fig. 1.

In carrying out this invention the walls of the tube may be made as thin as is necessary to give them such softness or yielding quality in lateral directions as is desirable, as the 90 thickness which it is necessary that the metal strips or springs should have for the purpose of my invention is not so great as to require any great thickness of the tube-walls for their incorporation thereinto and their inclosure 95 therein.

What I claim as my invention is—

1. A vaginal tube for a syringe consisting of a tube of soft flexible material and a series of flat metal strips or springs arranged within 100

the walls of said tube parallel with the length thereof and with their flat sides toward the internal and external circumferences of the tube, substantially as herein described.

- 5 2. A vaginal tube for a syringe consisting of a tube of soft flexible material and a series of flat metal strips or springs arranged loosely within the walls of said tube parallel with its

length for the purpose of giving it longitudinal stiffness while permitting its elongation, to substantially as herein described.

RUSSELL PARKER.
